ELECTRICAL SURGE RECORDER

John Henry Waghorne, Toronto, Ontario, Canada

Application January 15, 1948, Serial No. 2,484
In Canada June 10, 1947

5 Claims. (Cl. 346—74)

1

This invention relates to electrical recording devices and particularly to surge recorders of the electrostatic photo-sensitive type, in which a record of the characteristics of a surge is obtained through the instrumentality of a conducting electrode in engagement with a photo-sensitive surface, thereby producing so-called Lichtenberg figures.

It is a main object of this invention to provide a device of this character having a light-proof and weather-proof casing for containing the sheet of sensitized material on which the surge is to be recorded, the casing being so constructed that it may be readily dismantled to permit the film of sensitized material to be replaced.

It is another object of this invention to provide a surge recorder which may be coupled to high voltage lines or other electrical devices by connecting it on the line-side of the capacitance voltage divider.

It is a further object of this invention to provide a surge recorder that shall be simple and durable in construction, economical to manufacture and effective in its operation.

In electrical circuits, there are phenomena known as transient waves or surges which occur with changes of operating conditions. If the rate of voltage change of the surge is sufficiently low, a galvanometer may be caused to respond to, and indicate, the surge. However, there is a limit to the rate of voltage change to which any known mechanically movable element, having appreciable inertia, may be made to sensibly record. Such a surge may be caused in electrical circuits by various agencies, such as lightning, grounds of exceedingly short duration and other causes, and may adversely affect the operation of the circuit in accordance with the steepness, duration, amplitude and polarity thereof. It is therefore highly desirable that observation of these characteristics be obtained from an instrument that shall be easy to operate and that shall otherwise be adapted as a standard electrical instrument.

Apparatus of this nature for recording electrical surges was first disclosed in an article entitled "The Klydonograph" by J. F. Peters which appeared in Electrical World on April 10th, 1924. Such an apparatus is based on the phenomenon that if a voltage above a certain minimum value is applied between an electrode which bears on a photo-sensitive film and a neutral plane on the opposite side of the film, a latent image of a pattern will be produced on the film which image will of course be apparent after ordinary photo-

2

graphic development. The pattern has a characteristic design if the voltage is positive, and a different characteristic design if the voltage is negative. The diameter of the pattern is a function of the peak value of the voltage applied and hence, through proper calibration, the pattern can be used to measure the value of an applied voltage.

For a more complete description of the operating principles of such devices, reference is made to the aforesaid article by J. F. Peters and also to U. S. Patent No. 1,649,180 dated November 15th, 1927. Several improvements have since been made in this method of surge recording, including the recording of both a positive and negative figure regardless of the actual surge polarity by using a double film unit, as disclosed in U. S. Patent No. 1,702,412 dated February 19th, 1929.

There have similarly been many methods of coupling surge recorders to high voltage lines and other electrical devices in order to supply reduced voltage to the recording units. Various arrangements of rings, bars and insulator strings have been used to provide the capacitances to produce a voltage divider. However, they have all been large more or less permanent installations which are relatively expensive, and these frequently couple in some degree to other phases or circuits as well as to the one desired.

All of the foregoing and still further objects and advantages of the invention will become apparent from a study of the following specification, taken in conjunction with the accompanying drawings, wherein like characters of reference designate corresponding parts throughout the several views, and wherein:

Figure 1 is a view partly in elevation and partly in vertical cross-section of a completely assembled surge recorder constructed in accordance with this invention and shown connected to a power line,

Figure 2 is a perspective view of the said surge recorder,

Figure 3 is an exploded perspective view of the recording unit,

Figure 4 is a chart illustrating the direct calibration of a typical recording unit constructed in accordance with this invention for both positive and negative Lichtenberg figures, using a $1\frac{1}{2} \times 40$ microsecond surge, which surge is the one most commonly used in laboratory work to represent lightning, and is a non-oscillatory surge which rises to its peak value in $1\frac{1}{2}$ microseconds and falls to one half this value in 40 microseconds.

Figure 5 is a chart illustrating the calibration of the combined recording and coupling units with sensitivity control extensions of three different lengths, and

Figure 6 is a chart illustrating the potential distribution between a conductor and ground plane.

Referring particularly to Figures 1 and 3, the recording unit comprises two concave dishes 1 and 2 made of electrically non-conducting material disposed with their peripheries abutting one another to provide a hollow shell. Through the said dishes extend threaded rods 3 and 4 respectively, the said rods being secured to the respective dishes by oppositely facing pairs of locking nuts 5 and 6. Films of electrically conducting paint 7 and 8 are painted on a portion of the inside surfaces of dishes 1 and 2 respectively so as to be electrically insulated from one another, and these are respectively in electrical contact with the rods 3 and 4.

The inner end of each rod is hollowed out, and inserted therein are spring-pressed pins 9 and 10. Coiled around the rods are helical springs 11 and 12 respectively, one end of the said springs being soldered to the tip of the pin extending in the hollow portion of the rod and the other end of the spring being soldered to the outside of the rod in which it is inserted. The spring is therefore in tension when it is attempted to force the pin inside its rod, and therefore each assembly of rod, pin and tension spring provides a spring-pressed electrode.

The hollow shell provided by the two concave dishes with their peripheries abutting one another is divided by a flat partition of electrically non-conducting material 13 which is gripped between the peripheries of the dishes. Sensitized films 14 and 15 are disposed on opposite faces of the partition, and the spring-pressed pins 9 and 10 are in intimate contact therewith. If desired, the film may be in sheets cut to dimensions such that portions thereof may be gripped between the peripheries of the dishes. A rubber band 16 securely closes the assembly and makes it light-proof and weather-proof.

The coupling unit comprises an aluminum hood 20 through the center of which extends a bushing 21 provided with internal threads 22. An aluminum hinged hanger 23 is secured to the hood by means of the bushing 21 extending therethrough and the nut 24 which is screwed on the said bushing. At the opposite end of the hanger is a hook 25 provided with a screw clamp 26 whereby the device may be secured to a power line 27 or other power device wherein the surge is to be measured.

An extension 28 is secured to the outer end of rod 4. The length of the extension 28 which is used is determined by the operating voltage of the equipment under test; with different lengths of extensions different voltage ranges may be recorded. It is usual to choose an extension of a length such that it will record voltages greater than twice the normal line voltage, as surges below this value are not of interest.

With high operating voltages a dark spot may under some conditions be produced on the sensitized films even when no surges have occurred. A resistance of from 20 to 100 megohms may be connected between the two electrodes if it is desired to reduce the normal alternating current voltage across the recording unit so that it does not produce a dark spot on the sensitized film.

Thus resistor 29 may be connected between hood 20 and rod 4.

Remarks

It is an important feature of this surge recorder and of the method of coupling it to the line or other electrical devices that no physical grounded plane is used in conjunction with the electrode carrying the surge. However, since the unit is electrically symmetrical and shielded by the film of conducting paint on each one of the dishes, a neutral plane is established through the center of the unit. Thus, the recording is similar to that in a unit with a ground plane, except that twice the voltage is required to produce the same sized figures. In Figure 4 is shown a direct calibration of a typical recording unit constructed in accordance with this invention, for both positive and negative Lichtenberg figures using a $1\frac{1}{2} \times 40$ microsecond wave. To obtain this calibration, voltage surges of various known magnitudes are applied between the terminals of the recording unit (the recording unit of course having to be reloaded with fresh sensitized film after each voltage surge), and after the films are developed the radii of the patterns produced are plotted against the known applied voltages, as shown in Fig. 4.

Heretofore surge recorders have been coupled to high voltage lines and other electrical devices with the recording unit at the grounded end; this has required a small electrostatic capacitance from the unit to the line compared to the capacitance from the live terminal of the unit to ground or neutral plane. In accordance with this invention, the unit is coupled on the line side of the capacitance divider thereby reversing this condition of operation. This makes the recorder practically independent of location with respect to other circuits and to ground because the voltage distribution in the neighbourhood of a conductor is relatively independent of the location of the ground plane or grounded objects when the spacing between the two is greater than about 5 feet.

For a conductor of radius 0.04 feet (one inch diameter) the voltage distribution is shown in Figure 6, for values of conductor height of 5 feet and 20 feet above the reference plane. It will be seen from these curves that wide variations in the height of the conductor above the reference plane will have negligible effect upon the voltage adjacent the conductor, provided the conductor is at a height greater than 5 feet from ground. The hood 20 will not materially affect the voltage distribution as given in these curves (Figure 6) when it is mounted closely to the line. The hood is not intended to be nor is it a corona shield; it is an electrostatic shield, whose function is to control and reduce the effective electrical distance of rod 4 from the line, thereby allowing use of the device at high operating voltages without applying too high a voltage across the recording unit. This close proximity of rod 4 to the line makes the recording practically independent of variations in proximity of other lines or of grounded objects.

Figure 5 shows the calibrations for the recording and coupling units combined, using three different sizes of sensitivity-control extension 28. A $1\frac{1}{2} \times 40$ microsecond wave was used for these calibrations. It will be noted that the concave downward curvature seen in these curves is not present in the calibration curve of the recording unit per se shown in Figure 4; this cannot be definitely accounted for, but ionization around

the edge of the hood at the higher voltages may be a possible explanation of this variation.

The surge recorder disclosed herein may be installed and removed from the live high voltage lines or electrical devices by means of a treated wooden stick having a head designed to engage clamp 26.

It is thought that the construction and use of the invention will be apparent from the above description of the various parts and their purpose. It is to be understood that the form of my invention herewith shown and described, is to be taken as a preferred example of the same, and that various changes in the shape, size and arrangement of parts may be resorted to, without departing from the spirit of my invention or the scope of the subjoined claims.

What I claim as my invention is:

1. A surge recorder of the electrostatic photo-sensitive type for electrical apparatus, comprising a hollow non-conducting member having spaced walls disposed opposite to each other, an electrically non-conducting partition therebetween, a film of sensitized material on one side of the partition, a rod-type electrode secured to one of the said walls and having one end in contact with the film, another rod-type electrode secured to the other wall in substantial alignment with the first mentioned electrode and having one end adjacent to the other side of the partition, the other end of one of the said electrodes being adapted to be directly connected to the electrical apparatus in which a surge to be recorded passes, the other end of the other of the said electrodes being adapted to be electrostatically coupled to ground, and an electrically conducting electrostatic shield connected to the electrode which is adapted to be connected to the electrical apparatus, the said shield extending around the hollow member and being spaced from the electrode which is adapted to be coupled to ground.

2. A surge recorder of the electrostatic photo-sensitive type for electrical apparatus, comprising two concave dishes made of electrically non-conducting material disposed with their peripheries abutting one another to provide a hollow shell, a film of electrically conducting material on a face of each dish, the said films being spaced and insulated from one another, a partition of electrically non-conducting material adapted to divide the hollow shell at the abutting peripheries, a film of sensitized material on at least one face of the partition, a pair of rod-type electrodes disposed normal to the dishes in substantial alignment with each other and having their adjacent ends spaced apart by the partition, each of the said electrodes having an outer end extending through one of the dishes, and being in electrical contact with the film of electrically conducting material on a face of the dish through which it extends, means for electrically connecting the outer end of one of the electrodes to the electrical apparatus in which a surge to be recorded passes, and means for grounding the outer end of the other electrode.

3. A surge recorder of the electrostatic photo-sensitive type for electrical apparatus, comprising two concave dishes made of electrically non-conducting material disposed with their peripheries abutting one another to provide a hollow shell, a film of electrically conducting material on a face of each dish, the said films being spaced and insulated from one another, a partition of electrically non-conducting material adapted to

divide the hollow shell at the abutting peripheries, a film of sensitized material on each face of the partition, a rod-type electrode extending normally through one of the said dishes and having one end in contact with one of the films of sensitized material, electrically conducting means to secure the other end of the said electrode to the electrical apparatus in which a surge to be recorded passes, another rod-type electrode substantially in alignment with the first mentioned electrode and having one end extending through the other dish and in contact with the other film of sensitized material at a point opposite the point of contact of the first

10 mentioned electrode with a film, the end in contact with a film of at least one of the electrodes being spring pressed, each of the electrodes being in electrical contact with the film of conducting material on the dish through which it extends, 20 an electrically conducting open ended hood connected to the first mentioned electrode at a point outside the hollow shell and extending around the said hollow shell and being spaced from the other electrode, the other end of the said other electrode being adapted to be coupled to ground.

4. A surge recorder of the electrostatic photo-sensitive type for electrical apparatus, comprising two concave dishes made of electrically non-conducting material disposed with their peripheries abutting one another to provide a hollow shell, a partition of electrically non-conducting material adapted to divide the hollow shell at the abutting peripheries, a film of sensitized material on each face of the partition, a rod-type electrode extending normally through one of the said dishes and having one end in contact with one of the films, electrically conducting means to secure the other end of the said electrode to the electrical apparatus in which a surge to be recorded passes, another rod-type electrode substantially in alignment with the first mentioned electrode and having one end extending through the other dish and in contact with the other film at a point opposite the point of contact of the first mentioned electrode with a film, the end in contact with a film of at least one of the electrodes being spring pressed, an electrically conducting open ended hood connected to the first mentioned electrode at a point outside the hollow shell and being spaced from the other electrode and extending around the said hollow shell, the other end of the said other electrode being adapted to be coupled to ground, and a resistor of the order of 20 to 100 megohms connected 50 between the hood and the said other electrode.

5. A surge recorder of the electrostatic photo-sensitive type for electrical apparatus, comprising two conducting members one of which is adapted to be connected to the electrical apparatus and one of which is a rod-type electrode, a non-conducting partition between the conducting members, a film of sensitized material between the electrode and the partition and engaged by the electrode, an electrostatic shield of conducting material extending around and electrically connected to the conducting member which is adapted to be connected to the electrical apparatus and spaced from the other conducting member, and a resistor of the order of 20 to 100 megohms electrically connecting the two conducting members.
